UNITED STATES PATENT OFFICE

HARRY GEOCARES, OF CHICAGO, ILLINOIS

HAT CLEANING AND DRYING MECHANISM

Application filed May 17, 1929. Serial No. 363,958.

My invention relates to hat cleaning and drying mechanisms of the type adapted to so-called dry cleaning methods by which the cleaning is effected by the action of gasoline, 5 naphtha, or the like, as distinguished from cleaning by the action of soap and water. It is the object of my invention to provide a new and improved form and arrangement of parts by which the desired cleaning can be 10 effected quickly and easily with a minimum of care and attention on the part of the attendant, by reason of which the wear and tear on the hat being cleaned shall be reduced to a minimum, and by reason of which there shall 15 be the maximum of ability to control the cleaning operation so as to insure effective results.

It is one of the objects of my invention to 20 provide a new arrangement of parts for the use of a spray of cleaning fluid in connection with means for periodically immersing a hat more or less completely in the cleaning fluid, the arrangement being preferably such that the same means can be employed for the dry- 25 ing operation.

It is another object of my invention to improve mechanisms of this type in sundry details hereinafter pointed out. The preferred means by which I have accomplished my 30 several objects are illustrated in the drawings and are hereinafter specifically described. That which I believe to be new and desire to cover by Letters Patent is set forth in the claims.

35 In the drawings,—

Fig. 1 is a central vertical section through my improved machine, the lower portion of the supporting frame-work being broken away; and

40 Fig. 2 is an end view of the rack or cage by which a hat is held in position for the cleaning operation.

Referring to the drawings, 10 indicates a 45 receptacle, shown in the form of a casting made in one or more parts as may be desired, being mounted in the construction shown upon a supporting frame-work 11 of any suitable type. The receptacle 10 is provided with a transversely extending partition 12 near its lower end portion serving to provide

a reservoir for holding a supply of gasoline, naphtha, or other suitable cleaning fluid, the partition 12 being preferably in the form of a hopper with a valve 13 closing a central opening, such valve 13 being provided with 55 an operating rod 14 extending outwardly to a suitable handle 15 by the use of which the valve can be opened for permitting the naphtha to flow quickly into the lower end of the receptacle. 60

The receptacle 10 is provided at an intermediate point with a laterally extending sleeve 16, supported by a bracket 17 for holding a shaft 18 strongly in position in the sleeve. At its outer end, the shaft 18 is provided with a sprocket wheel 19 which is connected by a sprocket chain 20 with a sprocket gear 21 on the shaft 22 of a variable speed motor 23 supported by the sleeve 16, a suitable shield 24 being provided about the chain 20 and associated parts. 65

Upon the inner end of the shaft 18 within the receptacle 10, I have mounted a head 25 which supports a plurality of metal bows 26 in position to form a cage or rack for supporting a plurality of hats which are inserted through a reinforcing ring 27 which connects the ends of the bows 26. The arrangement is such that as the cage is rotated by power applied to the shaft 18 the several bowed bars 26 are carried successively into and through 70 the supply of naphtha or other cleaning fluid above the partition 12. 75

At a point in the side wall of the receptacle 10 opposite the ring 27, I have provided 80 a glass filled door 28 which can be opened downwardly upon a hinge 29 for insertion or removal of the hats. 85

In the lower end of the receptacle 10 below the partition 12, I have provided a rotary pump 30 of any suitable type operated by a horizontally disposed shaft 31 having its outer end portion connected with a motor 32 mounted upon the outer face of the wall of the receptacle. The pump is provided with 90 an inlet pipe 33 at its lowermost portion and is adapted to force the cleaning fluid upwardly through a pipe 34 to a spray head 35 supported by the pipe 34 directly above the rotary cage or rack, the spray head 35 being 95 100

provided with a series of openings in its lower face through which a plurality of streams of cleaning fluid may be forced downwardly through the cage.

5 In the construction shown, screen devices 36 and 37 of any suitable type are provided above the partition 12 and below the pump 30. A plug 38 closes a cleanout opening in the lower end of the receptacle. A vent pipe 39 leads upwardly from the lower end of the receptacle.

10 In the use of my improved mechanism, with the naphtha held in its elevated position above the partition 12 as shown in the drawings, one or more hats 40 are inserted in the cage or rack through the ring 27. The motor 23 is then started into operation at comparatively low speed so as to dip the hats into and out of the naphtha, the hats being carried 15 around by the cage and immersed at intervals more or less completely until thoroughly saturated. The valve 13 is then opened so as to permit the naphtha to pass quickly into the lower end of the receptacle. The motor 20 32 is then started into operation, serving to force the naphtha upwardly through the pipe 34 and out through the discharge openings in the spray device 35. The pump 30 is such as to cause the naphtha to be discharged from 25 the spray device 35 with considerable force so as to cause the naphtha to have a very strong impact upon the fabric of the hat and to cause the naphtha in most cases to pass through the fabric so as to insure effective 30 contact of the cleaning fluid with every portion of the hat. With the motor 23 running at such speed as to cause the one or more hats in the cage to be changing in position constantly, and with the spray device 35 delivering a great number of fine streams of 35 cleaning fluid downwardly with considerable force, the cleaning effect is very marked.

40 After the cleaning operation has been carried to the desired point for insuring effective 45 results, as can be determined by an inspection through the door 28, the motor 32 is to be stopped so as to cause a discontinuance of the spraying of the cleaning fluid. The motor 23 is then to be operated at high speed for 50 carrying the hats around very rapidly within the cage for drying the hats by centrifugal action.

55 While I prefer to employ the form of device substantially as shown in my drawings it is to be understood that I do not limit my invention to the form shown except so far as the claims may be so limited by the prior art, it being understood that changes may well be made in the construction without departing 60 from my invention.

I claim:—

65 1. A hat cleaning means comprising in combination a receptacle, a rotatable rack in said receptacle adapted to support a plurality of hats, means for rotating the rack, a spray

head above said rack in position to direct a great number of streams of cleaning fluid upon said hats as they are carried around by said rack, means comprising a valve for closing the receptacle at an intermediate point 70 above its lower end for maintaining effectively a body of cleaning fluid in said receptacle below said rack in such position that a hat carried by the rack is dipped into the fluid, and means for taking cleaning fluid 75 from the lower end of said receptacle after said valve means has been opened and driving it forcibly through said spray device against a hat on said rack.

2. A hat cleaning means comprising in combination a receptacle, a rotatable rack in said receptacle adapted to support a plurality of hats, means for rotating the rack, a spray head above said rack in position to direct a great number of streams of cleaning fluid 80 upon said hats as they are carried around by said rack, a downwardly tapered partition in said receptacle below said rack having an opening through its lower end, valve means for closing such opening adapted to maintain a supply of cleaning fluid below the rack 85 in such position that a hat carried by the rack is dipped therein, and means comprising a pump for taking cleaning fluid from the receptacle below said partition after said valve means has been opened and driving it 90 forcibly through said spray device against a hat on said rack.

3. The method of cleaning and drying a hat, comprising revolving the hat into and 95 out of a supply of cleaning fluid, directing a plurality of streams of cleaning fluid on and through the fabric of the hat, then draining the cleaning fluid away from the path of the rotating hat, and then rotating the hat at a 100 high speed for driving the cleaning fluid therefrom.
